METHOD OF FILLING AND SEALING FLAT BAGS

Bernhard Steinkemper, Karlsruhe, Baden, Germany

Application November 23, 1937, Serial No. 176,129
In Germany November 25, 1936

5 Claims. (Cl. 226—49)

The subject matter of the invention is a method of filling and sealing flat bags, which is distinguished by its particularly simple nature.

The known machines for filling and sealing flat bags are comparatively complicated and bulky in design. They require a relatively large amount of space and are also expensive to produce. To reduce the cost of production a new method is proposed, which is considerably more simple than that made use of in the known filling and sealing machines, which usually possess one, or two, revolving devices or long belt conveyors.

The new method resides principally in the fact that the flat bags, taken from a stack, are moved in the open condition to the filling point, where they are engaged by a double gripper, which on the one hand conducts the bags from the filling point to the gumming and sealing point, and on the other hand at the same time passes the bags, which at the gumming point have been furnished with adhesive and folded, to the pressing point, from where they proceed in the sealed and finished condition to the discharge. Owing to this measure not only a second revolving device is dispensed with, but as a matter of fact the entire revolver is for the greater part rendered unnecessary altogether, since in a manner of speaking merely a revolver segment is employed, which oscillates between the filling point and the gumming or the gumming and pressing point.

Filling and sealing machines operating according to this method may be made extremely simple in their complete design. They require little space, can be designed on simple lines, and are readily accessible in all parts.

Figs. 1 to 5 show details of a filling and sealing machine for flat bags operating according to the new method. Fig. 1 is an elevational view of the flat bag extraction. Fig. 2 is a plan view of the machine. Fig. 3 shows details of the pressing point, Fig. 4 the gumming, folding and sealing device and details of the movement of the nippers on the gripper arm, and Fig. 5 the gripper arm with its two pairs of nippers in plan.

45 The operation is as follows:

The empty flat bags 2 are taken from the stack of bags 1 by a wedge-shaped bag opener 3 secured to an oscillatory arm 5, which in turn is mounted on the rod 4, which moves upwards and downwards.

After the empty flat bags have been placed on the bag opener they are conducted in the open condition to the filling point 6 by a rocking of the arm 5 in the direction of the arrow. The material to be filled in passes from the container

7 into the measuring device 8, and is conducted from there in definite quantities into the filling hopper 6. The material then accordingly runs into the bag when the latter is located below the filling point.

The flat bags filled at the filling point are picked up by an oscillatory gripper arm 9. This gripper arm, as shown in Fig. 5, is of T-shaped design. On its two lateral arms there are mounted pairs of nippers 10 and 11. In accordance with Fig. 4, these nippers are moved over the levers 12, 13 and 14 by the tie rod 15. The entire gripper arm 9 together with the tie rod 15 performs by means of the shaft 16, on which it is mounted, a rotary movement.

If the pairs of nippers 10 are located at the filling point 6, the arm 5 moves the opened flat bags into position. These are filled, and at the same time the nippers 10 close and firmly grip the flat bag. When the filling operation has been completed the gripper arm swings in the direction of the arrow until the filled flat bag gripped by the nippers 10 has been moved into position below the gumming and sealing point (Fig. 4). On an arm 17 rocking in the direction of the arrow there is pivotally mounted at this point a second arm 18, on which there is provided the gumming strip 19. Upon the return movement of the arm 17 the arm 18 also swings back, the gumming strip 19 moving into contact with the gumming roller 20 and there picking up adhesive which, upon the forward movement of the arms 17 and 18, is transferred to the flat bag 2. After the adhesive has been applied to the flap of the filled flat bag the folding knife 22 rocking about the pivot 21 moves towards the front, whilst at the same time a folding bar moves out of the position 23 into the position 24. The folding bar, which moves along a circular path, is secured to a toothed wheel 25, which is actuated by the toothed segment 26.

After the filled and sealed flat bag has been firmly gripped at the gumming point by the folding bar 24 the nippers 10 open, whereupon the gripper arm 9 again returns to its initial position. Upon repetition of the operation the nippers 11 also close together with the nippers 10 and pick up the closed flat bag at the gumming point. When the gripper arm then again moves forwards the filled and sealed flat bags pass to the pressing point where, in accordance with Fig. 3, they are again firmly compressed and sealed down by the pressing jaw 21. The pressing device is actuated by the tie rod 28 by way of the angle lever 29.

55

After the flat bag has been firmly sealed at the 5 pressing point the nippers 11 open, and the gripper arm again returns. During this time the flat bags are still held by the pressing jaws, and are released when the gripper arm no longer forms an obstruction. They fall on to the sheet 10 30 secured to the arm 31, which is rotated by the shaft 32. In this connection it assumes a vertical position, so that the filled flat bags 33 are transferred to the discharge 34 in the upright condition.

The filling and sealing machine for flat bags 15 as described in the above represents merely a possible embodiment, in which the pieces of work or the flat bags are moved along a circular path. There is no objection also to conveying the flat bags in a straight line from the filling point to the gumming and folding point, and from there to the pressing point. The actual inventive idea 20 is to be regarded in the fact that the conveying device possesses a plurality of receiving points for the pieces of work and alternately takes over and delivers these simultaneously at different working points. The essence of the invention is not affected if in this connection the pieces of work 25 perform a straight or any other desired movement.

Having now particularly described and ascertained the nature of my said invention, and in what manner the same is to be performed, I declare that what I claim is:

30 1. In an apparatus for filling and sealing flat bags, means for extracting the bags from a stack, opening them and conducting them to the filling point in the open condition, and means including a swingable T-shaped gripper having a nipper on 35 each of the arms of the T of which one nipper engages the bags and conducts them from the filling point to a gumming, folding and sealing point, and the other nipper conveying bags which at the gumming point have been furnished with adhesive and folded to a pressing point.

40 2. In an apparatus for filling and sealing flat bags, means for extracting the bags from a stack, opening them and conducting them to the filling point in the open condition, a double gripper 45 adapted to perform a swinging movement, two pairs of nippers on the said gripper, the one of the said pairs of nippers engaging the bags at the filling point and conducting them to a gumming, folding and sealing point, and the second pair of nippers conveying the said bags to a

pressing point, and means for passing the sealed bags to the discharge.

3. In an apparatus for filling and sealing flat bags, means for extracting the bags from a stack, 5 opening them and conducting them to the filling point in the open condition, a double gripper adapted to perform a swinging movement, two 10 pairs of nippers on the said gripper, the one of the said pairs of nippers engaging the bags at the filling point and conducting them to a gumming, folding and sealing point, and the second pair of nippers conveying the said bags from the 15 gumming, folding and sealing point to a pressing point, means for engaging the said bags at the pressing point to permit of release and return of the 20 said nippers from the pressing point to their initial position, and means for passing the sealed bags to the discharge.

4. In an apparatus for filling and sealing flat bags, means for extracting the bags from a stack, 25 opening them and conducting them to the filling point in the open condition, a double gripper adapted to perform a swinging movement, two 30 pairs of nippers on the said gripper, the one of the said pairs of nippers engaging the bags at the filling point and conducting them to a gumming, folding and sealing point, and the second pair of nippers conveying bags from the gumming, 35 folding and sealing point to a pressing point, jaws at the pressing point which firmly grip the top 40 of the bag to permit of release and return of the said second pair of nippers to their initial position, and means for passing the sealed bags to the discharge.

5. In an apparatus for filling and sealing flat bags, means for extracting the bags from a stack, 45 opening them and conducting them to the filling point in the open condition, means including a swingable T-shaped gripper having a nipper on each of the arms of the T of which one nipper 50 engages the bags and conducts them from the filling point to a gumming, folding and sealing point and the other nipper conveying bags which at the gumming point have been furnished with adhesive and folded to a pressing point, an arm 55 rocking towards and away from the said pressing point, and a bag depositing means mounted on the said arm and conveying filled and sealed bags from the pressing point to the discharge.

BERNHARD STEINKEMPER. 50
